(57) **CLAIM**

The ornamental design for a tart pan, as shown and described.

DESCRIPTION

FIG. 1 is top perspective view of the tart pan in accordance with the present invention;

FIG. 2 is a bottom perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof;

FIG. 8 is a left side elevation view thereof;

FIG. 9 is a perspective view of a second embodiment of the tart pan in accordance with the present invention;

FIG. 10 is a front elevation view thereof;

FIG. 11 is a rear elevation view thereof;

FIG. 12 is a top plan view thereof;

FIG. 13 is a bottom plan view thereof;

FIG. 14 is a right side elevation view thereof;

FIG. 15 is a left side elevation view thereof;

FIG. 16 shows a perspective view of a third embodiment of the tart pan in accordance with the present invention;

FIG. 17 is a front elevation view thereof;

FIG. 18 is a rear elevation view thereof;

FIG. 19 is a top plan view thereof;

FIG. 20 is a bottom plan view thereof;

FIG. 21 is a right side elevation view thereof; and,

FIG. 22 is a left side elevation view thereof.

The broken lines in the drawings depict portions of the tart pan that form no part of the claimed design.
